UNITED STATES PATENT OFFICE.

JOSIAH BRADLEY, OF BROOKLYN, NEW YORK, ASSIGNOR TO ALBERT WESTLAKE, OF NEW YORK, N. Y.

SELF-ACCOMMODATING CRIMPING-DIE.

1,238,486.

Specification of Letters Patent. Patented Aug. 28, 1917.

Application filed March 25, 1916. Serial No. 86,571.

To all whom it may concern:

Be it known that I, JOSIAH BRADLEY, a citizen of the United States, and a resident of Brooklyn borough, New York city, and 5 State of New York, have invented certain new and useful Improvements in Self-Accommodating Crimping-Dies, of which the following is a specification.

My invention relates to what I call a 10 crimping die, by which I mean a grooved capping ring of peculiar construction, which coöperates with the crimping fingers of a capping tool or plunger, such as is used in bottle capping and sealing machines. The 15 function of this crimping die is to receive, guide and control the lower or free ends of the crimping fingers, so that the operations of the crimping fingers shall be steady, firm and accurate, throughout the entire capping, sealing and releasing of the bottle or 20 other container, upon which they act.

Owing to the fact that the lower ends of the fingers must be free to move in any direction laterally and because even a very 25 minute variance in the angle of lateral swing on the part of any of the crimping fingers, would throw it out of alinement with its particular groove, if the crimping die was fixed and unyielding, I have found it necessary 30 to mount the crimping die so that it can yield slightly in response to pressure from any direction and thus correct the finger variations without danger of breakage.

This self accommodating crimping die so 35 adapts itself to the variations of movement of the yoke that it always assumes and retains a level position during the capping and sealing operation, compensating and guiding the varying crimping fingers, so that their 40 initial variations are corrected and the work performed thereby is kept up to the desired standard. To call attention to this self-balancing and accommodating characteristic, I call my improved crimping die a self 45 accommodating crimping die.

In the accompanying drawings Figure 1 is a side elevation showing the plunger head and capping tool of a bottle capping and sealing machine, with a bottle about to be 50 capped; the self accommodating crimping die being shown in full lines in its initial position at the beginning of the capping operation and in dotted lines in its lowest position assumed during the operation.

Fig. 2 is a top plan partly broken away, 55 of the crimping die on line 2—2 of Fig. 1.

Fig. 3 is a vertical section on line 3—3 of Fig. 2.

Fig. 4 is a cross section on line 4—4 of Fig. 2.

Fig. 5 is a section on line 5—5 of Fig. 2.

Fig. 6 is a section on line 6—6 of Fig. 5.

Same letters indicate similar parts in the different drawings.

A represents a plunger head or arm carrying the plunger or capping tool B with the usual circular row of crimping fingers C. It also carries at its forward end a stop rod D and rises from the operating part of the machine through a turret E, which carries 70 the self-accommodating crimping die, which is the subject of this application.

The plunger is raised and lowered in the usual way by mechanism not shown and the turret is revolved intermittently by mechanism not shown.

The turret is provided with a number of lugs a, preferably four or six, to each of which is swiveled a yoke arm F, on which a crimping die G is swung. These yoke arms 80 are normally supported in a horizontal position, by means of a spring controlled pin b, which rests upon the coiled spring c, cased in a recess or chamber d on an arm e, mounted on the turret E.

As the turret revolves it brings each yoke arm F with its crimping die G into position directly under the plunger and directly over the milk bottle H or other container to be 85 capped and sealed.

It will be understood that the material, usually of disk form, from which the closure cap or seal is made, rests freely on top of the die plate or crimping die G and centered above the container to be capped. As the 95 plunger descends it pushes this disk and the crimping die downward to form the initial crimping of the ribs and presses down over the mouth and neck of the bottle until the crimping die reaches the lowest point of its stroke as shown in dotted lines in Fig. 1. At this time the yoke arm F turning upon the pivot f assumes the position shown in dotted lines in Fig. 1. It will also be understood that when the plunger contacts with 105 the crimping die, each of the fingers C, C, selects the nearest groove of the die, and entering the same is thereby held firmly

against lateral displacement during the downward and subsequent upward motion of the crimping die. During this time each finger is kept pressing against the bottle, as shown in dotted line in Fig. 1, by the pressure of the springs in the plunger B upon the upper ends of said fingers.

It is of course important that during this entire downward movement as well as during the return upward movement the crimping die should remain perfectly level and this is accomplished by slidably mounting the die plate G in two channeled brackets J, which are rockingly mounted or journaled in the yoke by the pins g, which are prevented from too easy or extensive turning by the springs h, fastened to the outside of the yoke arm at i.

It is also important that the crimping die should be kept centered both with regard to the plunger and the container to be capped. This is accomplished by the springs j, set in grooves in the body of the crimping die, one at each side, and as the spring controlled die plate is slidably mounted in the two channeled brackets J, the spring exerts a constant tendency to push the plate forward, relatively to the yoke arm F and the brackets by reason of the fact that said springs are compressed between the stops k, on the supporting brackets J and shoulders l on the die plate.

The natural effect of the springs j, would be to push the crimping die forward to the limit of the resilience of said springs. This

is counteracted by the stop rod D, which descends and ascends with the plunger B, keeping contact with the front edge of the guide plate so as to hold it back against the expansive force of said springs. This stopping action thus keeps the die centered over the bottle, in spite of the fact that the screw pivots g swing in an arc as the yoke arm F is depressed and raised under the alternate action of the plunger and spring pins b.

It will be readily understood that by this method of supporting the crimping die, the die is ready at all times to accommodate itself to the crimping fingers C and draw them gently into their normal position. To secure the exact centering of the die I provide a screw m, threaded into the crimping die and so arranged as to come against the supporting brackets J, simultaneously with the registering of the center of the die.

I claim:—

A self accommodating crimping die which comprises a pivotally mounted yoke arm, brackets pivotally mounted in said yoke arm, a die plate slidably mounted in said brackets, a capping die adapted to coöperate with said die plate, a stop for limiting the sliding movement of said die plate, and means for maintaining said die plate in engagement with said stop as said yoke arm swings upon its pivot.

JOSIAH BRADLEY.
